UNITED STATES PATENT OFFICE

2,144,397

ADVERTISING SIGN

Joseph Taddomio, East Boston, Mass.

Application February 9, 1938, Serial No. 189,600

25 Claims. (Cl. 40—130)

This invention pertains to advertising signs such as are designed to be supported at a substantial elevation, for instance projecting from the wall of a building or otherwise suspended over the sidewalk above a shop door, shop window or the like,—one object of the invention being to provide ready means whereby such a sign or at least essential portions thereof may be lowered to or near the sidewalk level for repairs or 5 for other manipulation or change of its constituent parts, and then may be restored to normal position so that such repairs or manipulation of parts may be performed easily and without recourse to the use of ladders.

Since signs of this type are often very heavy, it requires substantial effort to raise them to place, and a further object of the invention is to provide improved means for safely and easily raising and lowering such a sign or the operative elements 10 thereof and for positively locking it in normal position after it has been raised.

Signs of this general type are often of substantial length, and a further object of the invention is to provide raising and lowering means such 15 that the sign will remain level at all elevations and when raised fully will reliably assume the proper position for exhibition.

Signs of this kind frequently make use of electrical current, either for illumination or operation 20 of movable display parts, or both. When such a sign is designed to be lowered from normal position to the sidewalk level, for example, a distance which may be twenty feet or more, it is not always possible or convenient to provide a 25 flexible conductor of the proper length to maintain the circuit intact in all positions of the sign. A further object of the invention is to provide improved means operative automatically to close the circuit when the sign approaches normal position, but to break the circuit when the sign is lowered.

Modern signs frequently include complex mechanism, delicate and expensive parts and materials, etc., which must be protected from 30 the weather, and a further object of the invention is to provide a sign so devised that if the moving parts, display elements, etc., must at times be lowered for easy access, they are, nevertheless, fully and adequately protected from the weather.

When the sign includes as an element an endless supporting belt designed to carry the display cards or the like,—particularly when such cards are interchangeable, it is desirable to be able to move the support either forwardly or 35 backwardly at will when the sign is lowered

thereby to permit display cards or other elements to be exchanged at any part of the belt, without necessitating the removal of the belt, and a further object of the invention is to provide means whereby the belt may thus be moved.

It has been found difficult to move an endless display belt so as to maintain the display elements vertical, particularly when such elements are of substantial size, and a further object of the invention is to provide a sign so devised and arranged that the belt may be moved with the display elements in substantially horizontal position, although the characters upon said elements appear vertical when viewed by an observer with the sign in its normal position.

Further objects of the invention are to provide a sign of the class described so devised as to permit simultaneous display of different moving exhibits at its opposite sides; to provide adequate and efficient means for actuating such moving exhibits; to provide for equalizing the tension on a moving display exhibiting belt so as to insure its proper travel about the guiding and driving rolls; and otherwise generally to provide a sign of improved character and construction. These 20 and other objects and advantages will be more fully pointed out in the following more detailed description and by reference to the accompanying drawings wherein

Fig. 1 is a side elevation, with certain parts broken away, illustrating the improved sign mounted to project from a vertical surface, for example the wall of a building, but with the support for the display parts partially lowered;

Fig. 2 is a transverse vertical section through the housing which forms the upper or stationary part of the sign;

Fig. 3 is a fragmentary elevation illustrating mechanism useful in raising and lowering the 40 movable support;

Fig. 4 is a fragmentary transverse section to larger scale than Fig. 2 showing the support for the display mechanism housed in the upper stationary part;

Fig. 5 is an elevation of one side of the vertically movable support with portions of the display mechanism carried thereby;

Fig. 6 is a view similar to Fig. 5 but showing the other side of the vertically movable support, 50 the display belt being omitted;

Fig. 7 is a fragmentary plan view illustrating improved tension equalizing means for the endless band;

Fig. 8 is a fragmentary plan view showing parts 55

of tension regulating means for the conveyor belt;

Fig. 9 is a diagrammatic perspective belt illustrating the endless, card supporting display belt and the parts which carry it;

Fig. 10 is a side elevation of a device useful in manually raising and lowering the sign support; and

Fig. 11 is a fragmentary plan view illustrating means for locking the support in normal position.

Referring to the drawings, the numeral 1 (Fig. 1) designates a structure having a substantially vertical side wall, for example, the front of a shop or other building on which the sign is to be mounted. In accordance with the present invention the improved sign comprises a housing 2 (Figs. 1 and 4) which is supported by means of rigid struts 3 and 4 suitably anchored in the structure 1, and projecting horizontally outwardly from the latter. These struts 3 and 4 may be steel channel bars, angle bars or the like, and their outer ends preferably constitute portions of the frame of the housing 2. This housing is furnished with a weatherproof roof 5 of any suitable construction and material and preferably has closed ends 6, but is open at its bottom and is furnished with sight openings 7 and 8 in its vertical side walls. These sight openings may be provided, if desired, with glass or other transparent panels.

Normally the bottom of the housing is closed by the support 9 which carries the display mechanism of the sign. This support 9 may be of any suitable, rigid material, for example, wood or metal. When in its normal position the support is positively locked in place so that it can not accidentally drop from the housing by means of bolts 10 and 11, arranged to slide in guides on the bottom of the support, and which normally overlap the upper edges of the struts 4 or enter socket openings in such struts, as may be preferred. The bolts 10 and 11 are connected by links 12 to a cam disk fixed to a rotary stub shaft 13, having a slot 13^a for the reception of an actuator by means of which the shaft and disk may be turned manually for retracting or for projecting the bolts. An actuator suitable for this purpose is illustrated in Fig. 10 and comprises a rod 14 of a length sufficient to reach from the ground up to the shaft 13, the rod having a hook 15 or other suitable device at its end for engagement in the slot 13^a and having handles 16 and 17 at its opposite end whereby it may be held and rotated manually. Preferably, in order to provide proper momentum for turning the actuator 13, a balance wheel 18 may be secured to the rod 14.

A shaft 19 is journaled in the upper part of the housing 2, the axis of the shaft 19 extending longitudinally of the housing and preferably substantially midway of the width of the housing and in the space immediately below the roof 5. At one end this shaft extends outside of the housing and into a gear box 20 (Figs. 1 and 3). A worm gear 21 is secured to the end of the shaft 19 within the box 20 and meshes with a worm 22 which, through suitable gearing, may be driven by turning a stub shaft 23 having a slot 23^a designed to be engaged by the hook 15 of the actuator shown in Fig. 10. By engaging the hook 15 in the slot 23^a and then turning the handle 16, the shaft 19 may be slowly rotated, but by reason of the worm and gear mechanism, the shaft can not turn rapidly so as to allow the display mechanism accidentally to drop from the housing. Obviously if desired an electric motor sup-

ported for example on the struts 3 and suitably protected from the weather, may be arranged to drive the shaft 19 through proper reduction gearing, the motor circuit being controlled by a switch located at any convenient point.

In order to counterbalance the display mechanism, a long coiled spring 24 is arranged upon the shaft 19 within the housing, the spring being secured at one end to a collar 25 fixed to the shaft and having its other end 26 secured to the housing. This spring has a sufficient number of turns to permit the display mechanism to be lowered from the housing to the desired extent without unduly increasing the resistance offered by the spring, but on the other hand, the spring tends to counterbalance the weight of the display mechanism and to make it easier to restore the display mechanism to its normal position after being lowered.

At each end of the shaft there is arranged a pair of drums or pulleys 27 and to each drum is secured one end of a flexible suspension element 28 and 29, respectively (Fig. 2). As here illustrated, these suspension elements are thin, flexible, stainless steel ribbons, but it is contemplated that other types of flexible suspension device, for example, flexible cables, chains or the like, may be employed if desired. As illustrated for example in Figs. 2 and 4, the suspension elements 28 and 29 of each pair are so wrapped about their respective drums that when the shaft is turned, both suspension elements of both pairs will be wound up or paid out at substantially the same rate, according to the direction in which the shaft is turned, thereby raising or lowering the support while keeping it level at all elevations. The suspension elements 28 and 29 (Fig. 4) extend outwardly from the drums and about guide pulleys 30 and 31 at the upper parts of the side walls of the housing, and thence extend down along said side walls and are connected at their lower ends to the support 9, preferably adjacent to the corners of the latter, it being understood that a pair of suspension elements is arranged at each end of the housing.

The support 9 is preferably provided with a centrally disposed, vertical septum 30 substantially in the vertical plane of the axis of the shaft 19. At its opposite ends this septum is provided with guide fins 31 and 32 (Fig. 6) which are designed to be received in vertical slots 33 (Fig. 2) at opposite ends of the housing. These slots 33 are preferably formed by spaced parallel angle bars 34 whose lower ends diverge as shown at 35 (Fig. 2) so as to provide a flaring entrance 46 for the reception of the upper ends of the fins 31 and 32 as the support 9 is moved into the housing.

The support 9 preferably carries a removable protective casing comprising a top 36 (Fig. 4), end walls, and vertical side walls 37 and 38, the latter having large view openings through which the display elements within the casing may be seen. Preferably, these view openings in the casing are provided with glass panels 37^a and 38^a, so as to give adequate protection to the display mechanism, even when the support 9 has been lowered from the housing. The end walls of the casing are preferably furnished with screened ventilating openings protected by louvres at the outside of the casing, such openings being desirable to prevent overheating of the interior of the casing by radiation from the lamps. Preferably the top wall 36 of the casing has an elongate slot 75 for the reception of the upper edge of the septum 75

30 and the edges of this opening are provided with weather strips, for example strips of rubber so as to provide a tight seal and avoid any possibility that rain will enter the casing.

5 The support also carries a motor 39, preferably an electric motor, having a pulley 40 (Fig. 6) about which is trained a belt 41 which passes about a pulley 42 on a transverse shaft 43 mounted in journals in brackets 44 carried by the support 9, the shaft 43 passing through an opening in the septum 30. At the end of the shaft 43 opposite to that which carries the pulley 42 there is fixed another pulley 42^a (Fig. 5).

At opposite sides of the septum 30 are arranged 15 elongate supports 45 and 45^a, respectively, (Fig. 4), upon which are mounted parabolic reflectors 46 and 46^a having light sources 47 and 47^a at their respective foci. These light sources may each consist of one or more incandescent lamps, preferably lamps of the elongate tube type. The upper side of each reflector is normally closed by a light-transmitting guide or rest 48 and 48^a respectively, such guides or rests preferably being plates of glass. These guides may be wholly 20 transparent if desired, although it is preferred to employ material of a light-diffusing character such, for example, as frosted glass. If desired, either these rests 48 and 48^a or the light sources, or both, may be of such material or character as 25 to provide a colored illumination for the display elements.

Each of the rests 48 and 48^a, respectively, is designed to support a horizontal run 49 (Fig. 9) of an endless display carrier belt 49^a, for example 30 of the kind more fully disclosed in my copending application for patent, Serial No. 148,716, filed June 17, 1937, such carrier belt being designed to receive a series of display elements 50, for example cards or other substantially flat sheet-like parts having display characters thereon or therein, for example, characters consisting of series of perforations in the substance of the display element.

Below each of the supports 45 and 45^a, respectively, there is arranged a horizontal frame 51 or 51^a, respectively, carried by suitable brackets 52 or 52^a, each frame having at one end a horizontal shaft 53 or 53^a, respectively, on which is mounted a large pulley 54 or 54^a, respectively, and also a roller 55 or 55^a, respectively. At the opposite end of each horizontal frame 51 or 51^a there is arranged an extension frame 56 (Fig. 8) adapted to slide horizontally and carrying a guide roll 57. This extension frame is urged outwardly by means of coiled springs embracing suitable guide pins 58 mounted to slide in openings in frame member 51^x. Preferably one of these guide pins, for example, the pin 59, may be moved longitudinally by means of an adjusting lever 60 pivoted at 61 and having an opening for the reception of a screw-threaded post 62 which is engaged by an adjusting nut 63. By turning the nut 63 the lever 60 may be swung about its pivot 61 and thus the extension frame 56 may be canted slightly so as to swing the axis of the roll 57. The rolls 55 and 57 (Fig. 9), for example, constitute supports for an endless flexible conveyor C having a substantially horizontal run C' which forms a support for the inactive portion of the display carrier belt 49^a. The tiltable extension frame 56 provides not only for tensioning the endless conveyor belt, but also provides means whereby said belt may be so relatively tensioned at its opposite edges as to cause it to run true on its rollers 55 and 57.

The pulley 54 which turns the conveyor roll 55, is embraced by a cross belt 64 which passes about a pulley on a shaft 65 (Fig. 6) journaled in a frame 66 (Fig. 7) carried by the support 9. The shaft 65 also carries a pulley 67 (Fig. 6) 5 which is embraced by an open belt 68 which is trained about a pulley fixed on the shaft 43 closely adjacent to the pulley 42.

The shaft 65 (Fig. 7) carries a drive roll 69 located adjacent to one end of rest 48 for the 10 endless display conveyor belt 49^a, the latter also passing about a roll 70 (Fig. 6) journaled adjacent to the other end of the rest 48 and having associated therewith a weighted roll 71 designed to smooth out the display belt 49^a as 15 the latter moves upwardly and onto the rest 48.

In order to assure the true running of the display carrier belt 49^a over the pulleys 69 and 70, there is provided a roll 72 journaled in a tiltable frame 73 adjacent to the roll 69, the frame 73 20 being urged toward the roll 69 by means of a leaf spring 74. This frame may be tilted so as to change the angle between the axis of the roll 72 and that of the roll 69 by means of relatively 25 adjustable screws 75, so as to cause the roll 72 to pinch the display carrier belt adjacent to one edge or the other and thus to cause the belt to be biased in its travel toward one or the other end of the roll 69 thereby to center the belt properly. It is to be understood that belt driving 30 and guiding rolls like the rolls 69 and 70, together with belt adjusting means such as shown in Fig. 7, are arranged at the opposite side of the septum and cooperate with a belt like the belt 49^a whose horizontal run is guided by rest 48^a. This 35 second roll belt driving roll is carried by a shaft 65^a (Fig. 5) having a pulley 67^a driven by a crossed belt 68^a passing about pulley 42^a.

For guiding the belt as it moves toward the roll 70, suitable flexible smoothly curved guide 40 members 73^x are mounted on the support 9, and for straightening out the display belt as it approaches the roll 70, brushes 74^x may be provided.

Adjacent to each end of the septum 30 the latter is provided with racks 75^x having vertically 45 spaced slots 76 designed selectively to receive the lower edges of horizontally elongate-reflectors 77, 77^a, respectively, which overhang the rest 48 and 48^a. These reflectors diverge upwardly and outwardly from each other and are connected to the upper part of the septum 30 by means of rods 78 of adjustable length whereby the angle of inclination of the reflector may be varied at will. These reflectors may be of any suitable material, 50 but preferably are of metal and are preferably cylindrically curved. If desired, provision may be made for varying the curvature of these concave 55 reflectors.

An insulated distributor box 79 (Fig. 6) is 60 mounted upon the septum 30 and provides suitable sockets or the like for plugs at the ends of conductors designed to supply current to the lamps 47, 47^a and the motor 39. Conductors also lead from the box 79 to a pair of vertically elongate contact plugs 80 having tapered upper ends fixed to the guide fin 32 of the septum. These contact plugs are designed, when the support is in normal position, to engage complementary 65 sockets 81 (Fig. 1) carried by the housing and 70 to which suitable conductors lead from a source of electrical energy. The contacts 80 and 81 are so designed that when the support 9 is lowered from out the housing they automatically separate, but when the support is returned to its 75

normal position the contacts automatically re-engage so as to provide current for those parts of the display apparatus which require electrical energy.

5 In the operation of the device, it being assumed that the support 9 is in the position shown in Fig. 4, current is supplied to the lamps and to the motor 39. By means of the belt connections described the motor constantly rotates the rolls 69 (Fig. 9) and thereby moves the horizontal run 49 of the display belts 49^a along the rests 48 and 48^a respectively toward the left as viewed in Figs. 5, 6 and 9. As the display elements 50 move along these rests they are illuminated by the light sources 47 and 47^a and the images of these display elements are projected against the concave surfaces of the reflectors 17 and 18^a and by the latter are reflected downwardly and outwardly through the transparent panels 37^a and 38^a 10 in the casing and through the openings in the side walls of the housing so as to be visible to persons approaching the sign from either direction. Obviously, display elements exhibiting different characters may be provided at opposite 15 sides of the septum if desired. It will be noted that the display elements 50 are horizontally disposed in moving along the rests 48 and 48^a, and thus it is readily possible to use display elements of very substantial area even though they may 20 be thin and flexible, although as viewed by the observer the characters or other display features appear in upright position.

If it be necessary to change the display characters or otherwise manipulate the display mechanism, the entire display mechanism mounted upon the support 9 may readily be lowered from the housing to a convenient position, for example, to the sidewalk level. To accomplish this the actuator shown in Fig. 10 is first applied to the shaft 13 and rotated so as to retract the bolts 10 and 11, and is then applied to the shaft 23 and rotated so as to turn the shaft 19 and thus allow the suspension elements to unwind and permit the support 9 to move downwardly out of the housing,—the weight of the parts being nearly 25 but not quite counterbalanced by the spring 24. When the support 9 has been lowered to convenient position, it may be supported upon any suitable slightly elevated support or allowed to rest 30 upon the ground if preferred. The operator then lifts the protective casing from over the display mechanism and is then free to change the display elements 50, if desired, or to make repairs or adjustments such as may be deemed desirable, the 35 parts being readily available for this purpose.

For convenience in moving the display carrier belt when the support has thus been dropped from out of the housing (the motor then no longer being supplied with current) the pulley 61 may, 40 if desired, be provided with a socket for the reception of a handle 82, so that by throwing the drive belt 68 or 68^a off the pulley, the drive roll 69 may readily be turned, thereby to move the display belt along and allow the operator to have 45 access to its entire length.

When the changes or repairs have been made, the shaft 23^a is again rotated to wind up the suspension elements, and when the support has been restored to normal position, the bolts 11 and 12 50 are again projected to lock it in position.

While certain desirable arrangements of parts have been described whereby conveniently to obtain the objects of the invention, it is to be understood that the invention is not necessarily limited 55 to the precise construction herein specifically

disclosed but is to be understood as broadly inclusive of any and all equivalent constructions such as fall within the scope of the appended claims.

I claim:

1. A sign of the class described comprising a stationary housing having a weatherproof roof but open at its bottom, a display support normally substantially closing the open bottom of the housing, and means for raising and lowering the display support, said raising and lowering means comprising a shaft journaled in the housing, flexible suspension means connecting the support to the shaft and arranged to wrap around the shaft as the latter is rotated, and means for 10 rotating the shaft.

2. A sign of the class described comprising a stationary housing open at its bottom, a display support normally substantially closing the open bottom of the housing, means for raising and lowering the display support comprising a shaft journaled in the housing, flexible suspension means connecting the support to the shaft and arranged to warp about or to unwrap from the shaft as the latter is rotated whereby, upon rotation of the 20 shaft, the support is raised or lowered, said suspension means being so designed and arranged as to keep the support substantially level at all elevations, means comprising cooperating parts carried by the housing and support respectively 25 for guiding the support as it moves up into the housing, and means for rotating the shaft cooperating parts carried by the housing and support respectively, for guiding the support as it moves up into the housing.

3. A sign of the class described comprising a housing and means for supporting it in substantially horizontal position, the housing being open at its bottom, a support normally closing the bottom of the housing, means for moving the support up and down at will, display exhibiting means carried by the support, said exhibiting means including parts which consume electrical energy, contact elements carried by the support and forming terminals of an electrical circuit for said energy-consuming parts, and complementary contacts carried by the housing with 40 which the first contacts engage when the support is in operative position and from which the contacts carried by the support automatically separate when the support is lowered, and means for 45 supplying electrical energy to the contacts on the housing.

4. A sign of the class described comprising a stationary housing having a weatherproof roof but open at its bottom, a display support normally 50 substantially closing the open bottom of the housing, and means for raising and lowering the display support comprising a shaft journaled in the housing, flexible suspension means connecting the shaft with the support, means operative to turn the shaft thereby to wind up or to pay out the suspension means so as to raise or lower the support, and means for positively locking the support in normal position.

5. A sign of the class described comprising a stationary housing open at its bottom, a display support normally substantially closing the open bottom of the housing, and means for raising and lowering the display support, comprising a 70 shaft journaled in the upper part of the housing, a plurality of drums fixed to the shaft, flexible suspension elements wrapping the drums, said suspension elements being connected to the support whereby rotation of the shaft in one 75

or the other direction raises or lowers the support, respectively, means for turning the shaft, and rigid bolt members operative, when the support is in normal position, to lock the support to the housing.

6. A sign of the class described comprising a stationary housing open at its bottom, a display support normally substantially closing the open bottom of the housing, and means for raising and lowering the display support comprising a shaft journaled in the housing, suspension means connecting the support to the shaft, said suspension means being constructed and arranged to be effectively shortened or lengthened by rotation of the shaft in one or the other direction, respectively, and a spring operative substantially to counterbalance the weight of the support and the parts carried thereby.

7. A sign of the class described comprising a stationary housing open at its bottom, a display support normally substantially closing the open bottom of the housing, and means for raising and lowering the display support comprising a shaft journaled in the housing, flexible suspension elements each secured at one end to the support and attached at its opposite end to a part carried by the shaft so as to wrap about said part as the shaft is turned in one direction, and counterbalance means within the housing operative partially, at least, to counterbalance the weight of the support and the parts carried thereby.

8. A sign of the class described comprising a stationary housing open at its bottom, a display support normally substantially closing the open bottom of the housing, and means for raising and lowering the display support comprising a shaft journaled in the housing, and suspension means connecting the support to the shaft, said suspension means being so designed and arranged as to keep the support substantially level at all elevations, and means for rotating the shaft.

9. A sign of the class described comprising a display support, and means for raising and lowering the display support comprising a shaft journaled in fixed bearings, suspension means for the support connecting the latter to the shaft, gearing for turning the shaft, and a manually operable actuator, provided with a balance wheel, for driving the gearing.

10. A sign of the class described comprising a normally elevated display support, and means for raising and lowering the display support comprising a shaft journaled in fixed bearings, a coiled counterbalance spring encircling the shaft, flexible suspension means connecting the support to the shaft, and means for turning the shaft.

11. A sign of the class described comprising a normally elevated display support, and means for raising and lowering the display support comprising a rotary shaft, a plurality of drums fixed to the shaft, pairs of flexible suspension elements, each element being connected at one end to the support, each suspension element being partially coiled about one of the drums, the elements constituting both pairs being coiled in the same direction about the axis of the shaft, and means for turning the shaft including a worm gear mechanism operative to prevent sudden descent of the support.

12. A sign of the class described comprising a normally elevated display support, and means for raising and lowering the display support comprising a rotary shaft, two pairs of drums fixed to the shaft, a pair of ribbon-like flexible suspension

elements corresponding to each pair of drums, each suspension element of each pair being secured at one end to one of the drums of the corresponding pair, all of said elements being partially wrapped in the same direction about the drums to which they are secured, the free ends of the suspension elements being attached to the respective corners of the support, and means for rotating the shaft, and releasable means for holding the support in normal position.

13. A sign of the class described comprising a housing and means for supporting it in substantially horizontal position, the housing being open at its bottom and having view openings in its opposite sides, a support normally closing the bottom of the housing, means for moving the support up and down at will, the support having a pair of upwardly and outwardly diverging reflectors, and display means so arranged beneath the respective reflectors that an image of said display means is visible through the view openings in the sides of the housing when the support is in normal position.

14. A sign of the class described comprising a housing and means for supporting it in substantially horizontal position, the housing having view openings in its opposite sides, a support normally disposed within the lower part of the housing, the support having a centrally disposed, substantially vertical septum, a pair of divergent reflectors extending upwardly and outwardly from opposite sides of the septum, and movable display means disposed beneath each reflector so as to be visible by reflection through the view openings in the opposite sides respectively of the housing.

15. A sign of the class described comprising a housing and means for supporting it in substantially horizontal elevated position, the housing having view openings in its opposite sides, a support normally disposed within the lower part of the housing, the support having a substantially horizontal rest for a display element, and reflector means so disposed as to show a substantially upright image of a horizontally disposed display element resting upon the support as observed through the view opening in the side of the housing.

16. A sign of the class described comprising a normally elevated support having a substantially horizontal light-transmitting rest for a display element, means beneath the rest for illuminating a display element carried by the support, and a reflector so arranged above the rest as to show an upright image of a substantially flat sheet-like display element horizontally disposed on the rest.

17. A sign of the class described comprising a normally elevated support having a substantially horizontal light-transmitting rest for a horizontal run of an endless display carrier, a light source beneath the rest, and an inclined reflector above the rest having a reflecting surface so arranged as to show an upright image of a display element moving along the rest.

18. A sign of the class described comprising a normally elevated support having a substantially horizontal rest for a display element, means for illuminating a display element on the rest, and an elongate reflector above the rest, said reflector having a concave cylindrically curved reflecting surface.

19. A sign of the class described comprising an elevated housing and means for supporting it in substantially horizontal position, the hous-

- ing being open at its bottom and having view openings in its opposite sides, a support normally closing the bottom of the housing, and having a substantially horizontal light-transmitting rest 5 for display elements, an inclined reflector above the rest, and means for adjustably supporting the reflector whereby its angle of inclination to the horizontal may be varied.
20. A sign of the class described comprising a 10 housing and means for supporting it in substantially horizontal position, the housing being open at its bottom and having view openings in its opposite sides, a support normally closing the bottom of the housing and having a substantially 15 horizontal elongate light-transmitting rest for display elements, an inclined elongate reflector above said rest, means for adjusting the height of the reflector, and means for adjusting the angle of inclination of the reflector.
20. 21. A sign of the class described comprising a 20 housing and means for supporting it in substantially horizontal position, the housing being open at its bottom and having view openings in its opposite sides, a support normally closing the 25 bottom of the housing, the support carrying a casing having view openings in its sides which normally register with the view openings in the housing, means within said casing for moving a series of substantially flat horizontally disposed 30 display elements along a substantially horizontal path, means for illuminating the moving elements, and reflector means operative to show upright images of said elements through the openings in the casing and housing.
35. 22. A sign of the class described comprising an elevated housing and means for supporting it in substantially horizontal position, the housing being open at its bottom and having view openings in its opposite sides, a support normally closing 40 the bottom of the housing, a drive motor carried by the support, a pair of endless display carrier belts mounted on the support, means actuatable by the motor for moving said carrier belts simultaneously in opposite directions, display elements mounted on each carrier belt, means for illuminating the display elements, and reflector 45 means operative to show images of the display elements on the respective carrier belts when observed through opposite view openings of the housing.

23. A sign of the class described comprising an elevated housing and means for supporting it in substantially horizontal position, the housing being open at its bottom and having view openings in its opposite sides, a support normally closing the bottom of the housing, the support having a centrally disposed vertical septum, an endless display carrier mounted on the support at each side, respectively, of said septum, substantially horizontal light-transmitting rests for horizontal runs of each carrier respectively, a series of substantially flat display elements secured to each carrier, said elements being disposed substantially horizontally when moving along the respective rests, drive means for simultaneously moving the carriers in opposite directions, a light source beneath each rest, and a reflector disposed above each rest so arranged as to show an upright image of display elements moving along the rest when observed through the view opening in the corresponding side of the housing.

24. A sign of the class described comprising a 25 housing and means for supporting it in substantially horizontal position, the housing being open at its bottom and having view openings in its opposite sides, a support normally closing the bottom of the housing, a drive motor mounted on the support, a pair of substantially parallel shafts, connections from the motor for driving one at least of said shafts, a roller carried by 30 each shaft, an endless conveyor trained about said rollers, means for varying the position of the axis of one of said shafts whereby to bias the conveyor to run true about the rollers, an endless display carrier, and a substantially horizontal rest for an operative run of said carrier, inoperative portions of the carrier resting upon the conveyor so as to be moved by the latter.

25. A sign of the class described comprising a support, a drive motor mounted on the support, 40 a pair of substantially parallel shafts, connections from the drive motor for turning one at least of said shafts, a roller mounted on each shaft, an endless display carrier belt trained about said rollers, means for moving one of said shafts bodily toward and from the other to tension the belt, and means operative to tilt one of said shafts relative to the other whereby to bias the belt to run true about the rollers.

JOSEPH TADDONIO.
